UNITED STATES PATENT OFFICE.

OLAF BAKER, OF MIAMI, OKLAHOMA.

CHECK AND DEPOSIT-TICKET TRAY.

1,192,840.

Specification of Letters Patent.

Patented Aug. 1, 1916.

Application filed October 9, 1915. Serial No. 54,620.

To all whom it may concern:

Be it known that I, OLAF BAKER, a citizen of the United States, residing at Miami, in the county of Ottawa and State of Oklahoma, have invented a new and useful Check and Deposit-Ticket Tray, of which the following is a specification.

The present invention is a tray for use in bank bookkeeping, especially in connection with a "Burroughs" ledger posting machine, and it is the object of the invention to provide a tray adapted to hold the unposted and posted checks and deposit tickets or slips, whereby they may be readily posted and transferred from the unposted stacks to the posted stacks.

It is also the object of the invention to provide a tray of the nature indicated having novel means for holding or accommodating the unposted and posted checks and deposit tickets, so that the device will be convenient, time and trouble saving, and efficient in use.

It is also within the scope of the invention to provide a check and deposit ticket tray which is comparatively simple, compact and inexpensive in construction, the same being readily constructed chiefly of sheet metal, although various materials may be employed.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Figure 1 is a perspective view of the improved tray. Fig. 2 is a longitudinal section taken on the line 2—2 of Fig. 1. Fig. 3 is a cross section taken on the line 3—3 of Fig. 1.

In carrying out the invention, there is provided a suitable rectangular base 1 constructed of sheet metal or other material, and having thereon, four compartments, two for holding the unposted checks and deposit tickets, and the other for holding the posted checks and deposit tickets or slips.

One half of the base 1 is occupied by the compartments for the deposit tickets, and the other half by the compartments for the

checks. The compartment for holding the unposted deposit tickets or slips, embodies a rectangular plate 2 secured upon the base 1 adjacent one side edge thereof and near one corner. The plate 2 is disposed longitudinally of the base, and is provided at its side edges with a pair of upturned or upstanding ears 3 between which the stack of unposted deposit tickets T are disposed upon the plate 2, whereby the ears 3 hold the tickets in place against lateral displacement. The plate 2 is arranged adjacent the forward end of the base 1, and the rear end of the plate 2 is provided with an inclined abutment flange 4 overhanging the plate, and against which the head ends of the deposit tickets are adapted to abut, so that the other ends of the tickets will be shifted accordingly to project slightly one beyond the other so that the last mentioned ends of the tickets may be readily lifted by the fingers in removing the tickets as they are posted one at a time. The forward end of the plate 2 has an upwardly curved lip 5 for bending the tail ends of the deposit tickets upwardly, so that they may be more easily removed. This also tends to hold the deposit tickets against the flange 4. Secured upon the base at the other forward corner thereof adjacent the opposite side edge thereof, is a rectangular longitudinal receptacle or compartment 6 for receiving the posted deposit tickets T'. It will therefore be noted that the compartments for the unposted and posted deposit tickets are disposed side by side upon the base adjacent the forward end thereof. The receptacle or compartment 6 has disposed therein an inclined bottom plate 7 above the base 1 with its upper edge adjacent but spaced from the inner side of the receptacle 6 and provided with a downturned flange secured upon the base parallel with the inner side of the receptacle 6. The posted deposit tickets T' which are placed within the receptacle 6 upon the bottom plate 7 tend to slide against the outer wall of the receptacle 6, away from the inner wall, whereby the posted deposit tickets are held in proper position within said receptacle. The flange 8 forms with the inner side of the receptacle 6 a narrow pocket for receiving some of the posted deposit tickets T' which are out of alphabetical or numerical order. The base forms the bottom of said pocket, and the flange 8 is of less height than the inner side or wall of

the receptacle 6 and is adapted to support the slips adjacent said wall.

In order that the posted deposit tickets may be readily removed from the receptacle 6, the inner side of the receptacle is provided between its ends with an upwardly opening recess 9, and the bottom plate 7 is provided near its upper edge and between its ends with a recess 10 complementing the 5 recess 9 and extending downwardly within the flange 8. The thumb and fingers can be readily moved through the recesses 9 and 10 to grasp the posted tickets T' resting upon the bottom plate 7, so that they can 10 be removed easily.

A rectangular transverse receptacle or compartment 11 for the posted checks is mounted upon the base 1 adjacent the rear end thereof, the ends of the receptacle 11 20 being flush with the side edges of the base and being extended forwardly, as at 12, to provide end wings or members for the compartment or receptacle 13 for the unposted checks C. The inner side wall 14 of 25 the receptacle 11 provides a partition between the receptacles or compartments 11 and 13 to divide them, it being noted that the receptacles 11 and 13 are disposed side by side upon the rear half of the base, the 30 receptacle 13 being arranged adjacent the compartments for the deposit tickets.

The compartment 13 has an inclined bottom plate 15 having its upper edge disposed rearwardly and provided with relatively 35 wide depending flanges 16 secured upon the base, while the lower forward edge of the plate 15 has a relatively narrow down-turned flange 17 secured upon the base. A pair of standards 18-19 are engaged 40 through the plate 15 adjacent the lower edge thereof and secured to the base, the upper end of the standard 19 being curled or bent back, as at 20, to prevent the same from injuring the hand of the bookkeeper when the 45 checks are removed from the compartment 13 and placed into the receptacle or compartment 11. The bottom plate 15 is provided between its ends and adjacent its edges with recesses 21 extending into the flanges 50 16-17, for receiving the thumb and fingers to allow the checks C to be readily removed from the compartment 13. It will be noted that the checks C resting upon the plate 15 will slide against the standards 18-19, and 55 the lower edge of the plate 15 being raised slightly by the flange 16 will enable the checks C to be readily removed one at a time from the stack to be placed into the receptacle 11 for the posted checks.

60 The receptacle 11 is provided with an inclined bottom plate 22, the upper edge of which is disposed rearwardly adjacent but spaced from the rear side wall of the receptacle 11 and provided with a down-turned flange 23 secured upon the base. The

flanges 16 and 23 form with the respective walls of the compartments 13 and 11, pockets for receiving the checks when set on edge, as illustrated in Fig. 2. The bottom plate 22 is provided at its upper edge and between its ends with a recess 24 extending into the flange 23 for accommodating the thumb or finger when removing the posted checks C' from the receptacle 11. The rear wall of the receptacle 11 and partition 14 are provided between their ends with upwardly opening recesses 26 and 25, respectively, for accommodating the thumb and fingers in removing the checks, as will be apparent.

In using the tray for posting the checks 80 and deposit tickets, the unposted checks and deposit tickets are placed in stacks upon the plates 15 and 2, respectively. The deposit tickets will be held in place between the upturned ears 3 and against the flange 4, so 85 that they can be readily removed one at a time as they are posted. The stack of checks C resting upon the plate 15 will bear against the standards 18-19, and will be held against endwise movement by the wings or 90 extensions 12. Particular attention is directed to the fact that the unposted checks and deposit tickets are so arranged, that the names or signatures N will be disposed adjacent one another, which will make it more 95 convenient for the bookkeeper in referring to the signatures or names on the checks and deposit tickets. As the checks and deposit tickets are posted they are placed in the receptacles 11 and 6, respectively, which 100 can be done handily. Should the unposted checks be out of alphabetical or numerical order, those which are not in proper order can be set on edge within the pocket between the flange 16 and partition 14, so that they 105 can be readily placed in proper position at the proper time. The posted checks which are out of order can be placed within the pocket between the flange 23 and outer side wall of the receptacle 11, and the posted deposit tickets which are out of order can be set on edge within the pocket between the flange 8 and inner side wall of the receptacle 6. It is thus an easy matter to hold those 110 checks and deposit tickets which are not in proper order, so that they can be placed where they belong at the proper time.

The present device enables the checks and deposit tickets to be handled conveniently when posting them, and saves time and trouble compared with the ordinary methods employed. The entire device, with the exception of the standards 18-19 can be constructed inexpensively from sheet metal, although other materials may be employed, 115 and the device is also simple and light in construction.

Having thus described the invention, what is claimed as new is:

1. In a device of the character described, 120

- a base having a receptacle thereon, and a bottom plate within the receptacle for supporting a stack of slips and having a down-turned flange at one edge adjacent and spaced from the respective side wall of the receptacle to provide a narrow pocket for holding some of the slips when set on edge, the base forming the bottom of said pocket, said flange being of less height than said wall and being adapted to support the slips adjacent said wall.
2. In a device of the character described, a base having a receptacle thereon and an inclined bottom plate for said receptacle having a downturned flange at its upper edge secured upon the base and spaced from the respective wall of the receptacle, said bottom plate having a recess in its upper edge extending into said flange, and said wall of the receptacle having an upwardly opening recess complementing the aforesaid recess.
3. In a device of the character described, a base, an inclined bottom plate for supporting a stack of checks whose upper and lower edges are provided with downturned flanges secured upon the base, and standards adjacent the lower edge of said plate against which slips upon said plate rest, said plate
- being provided at its upper and lower edges 30 with companion recesses extending into said flanges, the lower recess being between the standards.
4. In a device of the character described, a base having a rectangular receptacle thereon whose ends are extended to provide the ends of a second receptacle, one of the side walls of the first mentioned receptacle forming a partition between the two receptacles, and the other side wall of the first mentioned 40 receptacle forming a back wall, said partition and back wall having upwardly opening recesses, inclined bottom plates for said receptacles having their upper edges provided with downturned flanges secured upon the base adjacent the back wall and partition, respectively, said bottom plates having recesses at their upper edges extending into said flanges, and standards at the lower edge of the bottom plate of the first mentioned 45 receptacle.

In testimony that I claim the foregoing as my own, I have hereto affixed my signature in the presence of two witnesses.

OLAF BAKER.
